UNITED STATES PATENT OFFICE.

LEE H. DOWNER, OF HOPEWELL, VIRGINIA.

PERPETUAL CALENDAR.

Application filed August 3, 1922. Serial No. 579,427.

To all whom it may concern:

Be it known that I, LEE H. DOWNER, a citizen of the United States, residing at Hopewell, in the county of Prince George and State of Virginia, have invented certain new and useful Improvements in Perpetual Calendars, of which the following is a specification.

This invention relates to improvements in perpetual calendars and has as one of its objects to provide a calendar which may be conveniently arranged at the termination of year periods to display a complete calendar for the ensuing year and one which may be conveniently consulted.

Another object of the invention is to provide a calendar which while simple in construction and capable of being manufactured at a low cost, will be durable and not subject to accidental displacement of its component parts.

In the accompanying drawings:

Figure 1 is a front elevation of the calendar embodying the invention;

Fig. 2 is a top plan view thereof;

Fig. 3 is a vertical sectional view on the line 3—3 of Fig. 1;

Fig. 4 is a similar view on the line 4—4 of Fig. 1;

Fig. 5 is a perspective view of one of the interchangeable blocks.

The calendar embodying the invention comprises a back board which is indicated in general by the numeral 1 and which may be of wood, metal, or any other material found suitable for the purpose, and this board is preferably of the oblong rectangular form shown in Fig. 1 of the drawings. The face of the board 1 is rabbeted at the lower edge 25 of the board as indicated by the numeral 2, and a strip 3 is secured within the rabbet and projects at its forward edge beyond the plane of the face of the board, the strip being provided in its upper side of its projecting edge portion with a longitudinally extending groove 4 the purpose of which will presently be explained. The face of the board 1 is formed with a series of transverse parallel grooves 5 which are equidistantly spaced with relation to each other and the lower one with relation to the strip 3. Strips 6 are seated and secured within the grooves 5 and these strips are provided in their upper and lower sides with grooves, which extend longitudinally thereof. Panels 8 are slidably adjustably mounted upon the face of the board 1 and are provided at their upper and lower edges with tongues 9 fitting in the grooves 7 in the strips 6, the tongue at the lower edge of the lowermost panel fitting in the groove 4 in the strip 3. These panels bear, in numerical order, ordinals representing the days in the several months of the year as indicated by the numeral 10. A fixed panel 11 is secured to the face of the board 1 near the upper margin thereof and extends longitudinally thereof preferably from the right hand edge of the board to a point spaced inwardly from the left hand edge, and this panel is provided in its lower edge with a groove 12 which receives the tongue 9 at the upper edge of the uppermost one of the month-date panels 8. The face of the fixed panel 11 bears letters 13 and 14, the former being representative of ordinary week days and the latter being representative of Sundays and being preferably printed in some distinguishing color such, for example, as red. Preferably the face of the panel 11 is divided by vertical lines 15 into spaces in which the letters 13 and 14 are printed, and it is also preferable that the faces of the strips 6 be provided with similar lines of division indicated by the numeral 16 and defining spaces 17 located in vertical alinement beneath the letters representative of the ordinary week days, and other spaces 18 located in vertical alinement beneath the letters representative of Sundays. The latter spaces are preferably of a distinguishing color as shown clearly in Fig. 1 of the drawings. It will now be evident that the month-date panels 8 are adapted to be slidably adjusted in the respective channels in which they are arranged upon the face of the board 1 and that they are adapted to be positioned so as to bring the ordinals "1" borne thereby in vertical alinement beneath the proper date letters upon the panel 11, in accordance with the week day upon which the first of each month of a given year will fall. In order that the panel 8 may be conveniently adjusted, each panel is preferably provided at its left hand edge with a finger piece 19, and in order that the panels may be held in positions of adjustment and therefore prevented from being accidentally disarranged after they have been suitably positioned for an ensuing year, openings 20 are provided extending through the board 1, and each panel 8

is provided near its finger piece 19 with an opening 21 adapted to register with one or another of the openings 20, a cotter pin or like securing element 22 being fitted through 5 the registering openings for the purpose stated and as best illustrated in Fig. 4 of the drawings.

The panels 8, as stated, bear ordinals arranged in numerical order and representing 10 the days of months, and the said panels are twelve in number and are arranged one beneath another and are representative of the twelve months of the year. Therefore, each panel will bear ordinals ranging from one 15 to thirty or thirty-one, as the case may be, except that panel which is second in order and which is representative of the month of February and which will of course bear ordinals ranging from one to twenty-eight. 20 To provide for leap year, the board 1 is provided near its right hand edge with a series of openings 23 corresponding to the openings 20 located within the channel which accommodates the panel 8 representative 25 of the month of February, and one or more month day blocks 24 are provided bearing the ordinal "29" as indicated by the numeral 25, the blocks being provided with tongues 26 corresponding to the tongues 9 30 of the February panel 8. Likewise each block is provided with an opening 27 through which and any one of the openings 23, a cotter pin (not shown) corresponding to the pin 22 may be fitted. Upon the occurrence 35 of a leap year one of the blocks 24 will be fitted into the channel which receives the February panel and in position abutting against the right hand end of said panel and secured in place by the cotter pin which is passed through the openings 23 and 27.

In order that the various panels 8 may be suitably identified, a panel 28 is secured upon the face of the board 1 at the left hand margin thereof and is provided at its lower 45 margin with a tongue 29 seating in the groove 4 in the strip 3, the said panel being provided upon its rear face at its upper end with a boss 30 seating in a recess 31 provided in the face of the said board 1. Also this end of the panel 28 is provided in its upper edge with a groove 32, and a block 33 is seated and secured within a recess 34 formed in the upper left hand corner of 55 the face of the board 1 and is provided in its lower side with a groove 35 located above and opposite the groove 32. The numeral 36 indicates numeral blocks which are provided at their upper and lower ends with tongues 37 slidably fitted into the grooves 32 and 35, and these blocks bear upon their faces 60 ordinals which are indicated by the numeral 38, and the said blocks are selected from a stock and are arranged to effect a composition 65 of ordinals representing the current

year. The panel 28 bears upon its face a series of month abbreviations 39 which are located opposite the left hand ends of the channels in which the month panels 8 are arranged.

In order to accommodate the stock from which the blocks 36 are selected and also to accommodate the blocks 24 heretofore referred to, a strip 40 is seated and secured within a rabbet 41 formed in the rear face of the board 1 at the upper edge thereof and is formed with a longitudinal groove 42 in its upper marginal portion, this groove being adapted to receive the tongues 26 and 37 of the blocks 24 and 36. Likewise the 70 projecting upper edge portion of the panel 11 is formed with a groove 43 which opposes the groove 42, and the block 33 is formed with a similar groove 44 likewise 80 opposing the groove 42, these grooves 43 and 44 being adapted to receive the tongues at the opposite ends of the said blocks 24 and 36. In this manner provision is made at the upper edge of the board for storing a sufficient supply of ordinal blocks to meet all 90 the requirements, and in the ordinary use of the device, this stock will be substantially concealed from view, or at least will not be confused with the blocks or panels which are arranged upon the face of the board. The blocks 36 are adapted to be secured in place in the same manner as the panels 8 and the blocks 24, as previously described.

Inasmuch as the cotter pins 22 are not subjected to any strain tending to pull them out from the openings 20 and 23 in the board 1, but are merely intended to prevent sliding movement of the strips 8 or pieces 24 as the case may be, it is preferable that they be formed of spring metal and have their 105 stem members bowed outwardly in opposite directions and somewhat spread apart so as to fit frictionally in the openings in the said board 1 as shown clearly in Fig. 4 of the drawings. By this arrangement the pins may be conveniently removed and reinserted as occasion requires and without the necessity of dismounting the board or bending 110 the ends of the stem members of the pins.

Having thus described the invention, what is claimed as new is:

1. A calendar comprising a body member provided at one face with a series of parallel channels, month indicating means at one end of the channels, month-date bearing panels slidably adjustably mounted in the channels, the panels and the body member being provided with openings adapted to be brought into registration in the adjustment of the panels, and a securing element 120 removably fitted through the registering openings.

2. A calendar comprising a body member provided at one face with a series of parallel horizontal channels, month indicating 130

- means at one end of each of the channels, means above the series of channels to indicate the week days, and a series of month-date bearing panels slidably adjustably 5 mounted in each of said channels and arranged consecutively and corresponding in number to the number of days in the respective month.
3. A calendar comprising a body member provided at one face with a series of 10 parallel horizontal channels, month indicat-
- ing means at one end of each of said channels, means above the series of channels to indicate the week days, a series of month-date bearing panels slidably adjustably 15 mounted in each of the channels and consecutively arranged and equal in number to the number of days in the respective month, and means for securing the panels in positions of adjustment. 20

In testimony whereof I affix my signature.

LEE H. DOWNER. [L.S.]
